UNITED STATES PATENT OFFICE.

GUSTAV A. J. MEYER, OF CHICAGO, ILLINOIS, ASSIGNOR TO MEYER & WENTHE, OF CHICAGO, ILLINOIS, A COPARTNERSHIP CONSISTING OF GUSTAV A. MEYER AND HERMAN H. WENTHE.

SEAL PRESS.

Application filed October 8, 1923. Serial No. 667,166.

To all whom it may concern:

Be it known that I, GUSTAV A. J. MEYER, a citizen of the United States, residing at Chicago, in the county of Cook and State 5 of Illinois, have invented certain new and useful Improvements in a Seal Press; and I do hereby declare the following to be a full, clear, and exact description of the invention, such as will enable others skilled 10 in the art to which it appertains to make and use the same.

My invention relates to portable seal presses of the general class commonly known as pocket seal presses, and in its 15 general objects aims to provide novel and advantageous means for latching the actuating lever of the seal in a depressed position and for preventing the movable die of the seal from rotating with respect to the stem 20 carrying the same.

More particularly, my invention provides a simple and cheaply manufactured latching construction so disposed that the latch can readily be manipulated by a finger of 25 the hand holding the seal, and also disposes the latch so that it will not be apt to have the lever catch on the same when the latch is in its released position. Furthermore, my invention arranges the cooperating lever 30 and latch portions so that when the lever is latched in its depressed position, the spring employed in the seal for raising the lever will also operate for retaining the latch securely locked, thereby preventing 35 an accidental unlatching of the same.

My invention also provides simple means for preventing an accidental rotation of the movable die, and provides the arrangement for this purpose in a construction which 40 will not interfere with the ready detaching of this die. Furthermore, my invention provides a construction in which both this last named feature and the latching arrangement can readily be applied to a 45 pocket seal having a body of cast metal, without requiring extensive machine work and without involving an undesirable weakening of any of the parts.

Still further and also more detailed objects will appear from the following speci-

fication and from the accompanying drawings, in which—

Fig. 1 is a side elevation of a pocket seal press embodying my invention, showing this with the actuating lever latched in its de- 55 pressed position.

Fig. 2 is a plan view of the seal press, taken with the lever and latch in the same position.

Fig. 3 is a view similar to Fig. 1, with 60 portions of the seal press in a central vertical section taken longitudinally of the press.

Fig. 4 is a fragmentary elevation of the seal press, with a part of the lever cut away 65 to show the lever in its latched position.

Fig. 5 is an enlarged perspective view of the latching member.

Fig. 6 is an enlarged perspective view of the sleeve which guides the stem of the mov- 70 able die.

In the illustrated embodiment, the seal press of my invention comprises a cast body provided at its rear end with a ring 1 adapted to be engaged by one finger of the 75 hand holding the seal, this body having its forward end forked to provide a lower horizontal plate 2 upon which the usual counter of the die is formed, the body having on the upper arm of the fork a hollow 80 stem or riser tube 3 in axial alinement with the said lower plate. The bore of the riser tube 3 has its lower portion contracted to a smaller diameter as shown in Fig. 3 and this smaller diameter portion affords a 85 guide for a sliding sleeve 4. Extending through this sleeve 4 is a shank 5 of a screw which is threaded at its lower end into the stem 6 of the movable die plate 7. This screw has a head 8 of a cylindrical contour 90 slidably fitting the main and larger diameter portion of the bore of the hollow stem or riser tube 3, so that this head will be guided by its engagement with the upper bore portion and will cooperate with the 95 sleeve in maintaining the axis of the movable die plate in a constant position.

To prevent the movable die plate from rotating with respect to the lower die plate, I provide the sleeve 4 at its lower end with 100

minute teeth 9 which press into the top of the stem 6 when the screw is tightened, thereby preventing the movable die plate from rotating with respect to the sleeve 4.

5 I also provide this sleeve, desirably at its upper end, with a laterally projecting finger 10 which is slidably guided in a vertical slot formed in one side of the riser tube 3 as shown in Figs. 1 and 2. Thus arranged,

10 the said slot and finger cooperate in preventing the sleeve from rotating with respect to the body of the press, while the teeth 9 hold the movable die plate stationary with respect to the sleeve, so that all of

15 the elements just named cooperate in preventing the movable die plate from rotating about its own axis. However, upon loosening the screw, the grip of the teeth 9 is released, so that the movable die plate

20 can readily be detached or replaced.

Disposed within the bore of the riser tube 3 between the bottom of the head 8 of the screw and the bottom of the larger diametered portion of the said bore is a spiral 25 spring 12, which spring is continuously under compression and hence steadily tends to raise the said screw and the movable die plate carried by the latter. In being raised by the spring, the die plate moves the handled lever which forms the actuating member of the seal. This lever is desirably pivoted on a pin 13 extending transversely of the seal at one side of the said bore in the tube 3 and near the lower end of the latter, and the lever is desirably of a forked bell-crank formation with a lower arm 14 carrying a roller 15 adapted to travel upon a washer 16 which rests upon the top of the movable die plate 7. The longer or forked 30 arm of the lever straddles the upper part of the forked body of the press and extends rearwardly of the latter to form a handle 17. This longer and handled arm of the lever is provided at the inner edge of the bight of its fork with a notch 18 for receiving the stem 19 of a latching member. The latching member desirably comprises a fork having arms 20 straddling a relatively narrow ribbed portion 21 of the press body and pivoted to this rib on a transverse pin 22, and the said fork of the latching member is connected by the stem 19 to a finger-piece 23 as shown in Fig. 5.

The entire latching member is desirably 55 of such a size that it can readily be swung forwardly against the upper rear edge of the riser tube 3, as shown in Fig. 3, thereby permitting the fork of the handled actuating lever to swing freely over it when the lever is raised or depressed. When the press is to be compacted, the lever is first depressed and the latching member is then swung rearwardly about its pivotal mounting, whereupon the stem 19 enters the notch 18 and a subsequent raising of the handled

lever portion through the action of the spring is prevented by the engagement of the top of the lever with the lower edge portions of the finger-piece 23. The latched seal press is then disposed as shown in Fig. 70 1, which figure also shows that the finger-piece is in a position where it can readily be pushed out of its latching relation by the thumb of the hand holding the seal.

To prevent the latch from slipping out of its latching position accidentally, I desirably form the portions of the handled lever at opposite sides of the slot 18 so that they will slope upwards forwardly of the press, thereby presenting an acute angle towards the forward face of the finger piece and affording a hump over which the finger-piece would have to ride if any jarring tended to slip it out of its latching position. However, the proportioning of the 85 parts is such that the lever is slightly raised when thus latched, thereby permitting the latch to be released instantly by first depressing the lever for the rest of the way so that the finger piece can readily clear 90 the said notched edge portion of the fork in the hand lever.

It will be obvious from the above that the latching arrangement of my invention is exceedingly simple, easily manipulated 95 and inexpensive in construction; that the lifting action of the single spring 12 of the press also operates to hold the latch in its locked position, so that no additional spring is required for this latter purpose; and that 100 no auxiliary fastenings or other elements are required on the lever of the press. So also, it will be evident that the provisions for preventing the rotation of the movable die plate of the press are exceedingly simple and inexpensive in construction, particularly as the rotation preventing guide 105 metal can readily be formed out of sheet metal as shown in Fig. 6 and that the bolt head cooperates in guiding the sleeve so as 110 to maintain the axis of the movable die plate fixed with respect to the press body.

However, while I have illustrated and described both of these important features of my invention in a highly desirable embodiment, I do not wish to be limited to the joint use of the same. Neither do I wish to be limited to the various details of construction and arrangement here disclosed, it being obvious that they might be varied 115 in many ways without departing either from the spirit of my invention or from the appended claims.

I claim as my invention:—

1. In a seal press, a frame having a lower 125 arm and an upper arm formed with a narrow ribbed top part and a tubular part extending above the ribbed part, a spring pressed die-carrying shank in the tubular part, a forked lever for operating said die 130

- pivoted to the frame and formed with a notch at the bight of the fork, and a latch having a forked lower end straddling and pivoted to the said ribbed top part of the frame adjacent to said tubular part and having a substantially T-shaped head the shank of which head is received in the notch of the lever and the top of which engages the upper face of the lever to hold the latter depressed, said latch in inoperative position being disposed below the lever and with its top resting against said tubular part of the upper arm of the frame.
2. In a seal press, a frame having a vertical bearing, a spring pressed die-carrying shank in the bearing, a forked lever for operating the die pivoted to the frame and formed with a notch at the bight of the fork, and a latch pivoted to the frame adjacent to said bearing so as to rest against the latter in inoperative position and be disposed beneath the lever, the latch being formed to engage said notch of the lever to hold the latter depressed, the latch in inoperative position being received in the space provided by the forked part of the lever.
3. In a seal press, a frame having a vertical bearing, a spring-tensioned die-carrying member in the bearing, a lever pivoted to the frame for operating said member, and having a slotted part receiving the bearing, and a latch pivoted to the frame and disposed to rest against the bearing in inoperative position and in registry with the slotted part of the lever, whereby upon depression of the lever to latch same in inoperative position, the latch will project through the slotted part of the lever thereby to render same visible and to permit same to be moved about its pivot to latch the lever in depressed position.
4. In a seal press, a frame having a vertical bearing, a spring-tensioned die-carrying member in the bearing, a lever pivoted to the frame for operating said member and having a slotted part and a relatively short latch pivoted to the top of the frame and closely adjacent to the bearing and to the lever so as to be substantially housed by the lever, the lever having a slotted part through which the latch is visible and projects upon depression of the lever to allow the latch to be moved into latching engagement therewith.
5. In a seal press, a frame having a vertical bearing, a spring-tensioned die-carrying member in the bearing, a lever pivoted to the frame for operating said member and having a slotted part and a relatively short latch pivoted to the top of the frame and closely adjacent to the bearing and to the lever so as to be substantially housed by the lever, said latch in inoperative position resting at an incline against the bearing and with its upper end extending above the top of the bearing, the lever having a slotted part through which the latch is visible and projects upon depression of the lever to allow the latch to be moved into a vertical position in latching engagement with the lever.

Signed at Chicago, Illinois, October 1, 1923.

GUSTAV A. J. MEYER.
